CLAIM

The ornamental design for a ribbon holder, as shown and described.

DESCRIPTION

FIG. 1 is a top perspective view of a ribbon holder showing my new design;

FIG. 2 is a bottom perspective view thereof;

FIG. 3 is a top plan view thereof;

FIG. 4 is a bottom plan view thereof;

FIG. 5 is a side elevation view thereof, the opposite side being a mirror image; and,

FIG. 6 is a top perspective view thereof, showing the ribbon holder in used condition.

The broken line showing of the ribbon in FIG. 6 depicts environment subject matter and forms no part of the claimed design.

It is understood that the apertures in FIGS. 1-4 and 6 are being continuous along the path indicated by the dot-dash lines.
